UNITED STATES PATENT OFFICE.

ANTON MATUSCHAK AND ALBERT LANGSCH, OF NEW YORK, N. Y.

ATTACHMENT FOR FILLING BARRELS.

Application filed November 16, 1921. Serial No. 515,451.

To all whom it may concern:

Be it known that we, ANTON MATUSCHAK and ALBERT LANGSCH, citizens of Austria and Hungary, respectively, residing at New York, in the county of New York and State of New York, have invented certain new and useful Improvements in Attachments for Filling Barrels, of which the following is a specification.

This invention relates to filling devices, and more particularly to that type used in filling barrels or other similar containers, and the main object is to provide a device which will automatically stop the flow of liquid passing into a barrel at any predetermined level, thus making the device particularly useful to industries where fractional mixing of solutions are required.

Another object is to provide ready means of checking or completely stopping the flow of liquid before the automatic-closing mechanism acts, this means being used to prevent accidental overflow in the event that the automatic closing means not functioning or closing the valve at any time during the filling.

These and other objects will become apparent in the description below in which the characters of reference refer to the like-named parts in the drawings.

Referring briefly to the drawings:—

Figure 1 is a transversely sectioned side elevation of the complete device, and showing the valve in the closed position.

Figure 2 is a front elevational view showing the inlet opening.

Figure 3 is a top plan view of the device.

Figure 4 is a rear end elevational view of the same showing the valve opening push button.

Figure 5 is an exterior side view of the device.

Figure 6 is a fragmentary transverse sectional view showing the valve in open position.

Figure 7 is a horizontal sectional view, through the main body, taken on the line 7-7 of Figure 6.

Figure 8 is a fragmentary sectional view illustrating the means for retaining the valve in open position.

Referring to the drawings more in detail, in which the numeral 10 represents a relatively long tubular member having elongated slots 11 cut through the wall thereof. The lower end of member 10 is formed into

a double chamber by the conical roof 12. The chamber 13, beneath roof 12, houses a metal float 14. The upper end of member 10 has an external thread below which is formed a shoulder flange 15, upon which the main body 20 rests. The threaded surface 16 of member 10 receives a nut 17 and a jam nut 18, the latter adapted to permanently position nut 17 for insuring uniformity of depth when filling a series of barrels. Legs 19 extending from member 17 grip the body of the barrel when the device is secured in place.

The main body 20 is secured to the upper threaded portion of member 10 and has two intercommunicating chambers 21 and 22 which are sealed from each other by a valve 23. The legs 24 of the valve retain the valve 23 in position, with respect to hole 25 while in open position. A hollow stud 26, formed on the upper surface of the valve 23 and having a spring 27 therein, slidably engages hole 28 of the hexagonal head 29. The tension of spring 27 normally keeps the valve 23 on its seat.

Screws 36 form bearings for a pivotally mounted shaft 36 which has levers 34 and 37 secured thereto, both extending outwardly therefrom in opposite directions to each other. Lift rod 38 is hingedly connected to lever 37, at one end, while the opposite end engages a countersunk hole on the underside of valve 23. A plunger 31, surmounted by a push button 32, is also hingedly connected to the other lever 34 by screws 35, the latter being retained in slot 33 of lever 34. By referring to Figures 1 and 6, it will become apparent that, as the push button 32 and plunger 31 are depressed, lever 34 will be rotated downwardly, while the opposite lever 37 describes an upward movement, thus lifting valve 23 from its seat.

In this position the fluid can pass through strainer 41, thence into chambers 21 and 22 after which it passes downwardly through the tubular member 10 and flows into the barrel through holes 11.

A pawl 39, formed to the end of the lever 34, retains the latter in the lower position by engaging the underside of a hinged hook member 40. A horizontal plate 45, having a slot 44 at its outer end, is secured to the hinged hook 40. A nut 46, slidably secured in slot 44, has one end of a threaded rod 42 secured therein, the latter extending down-

wardly through guard tube 47, and is secured at its lower end to the float 14. It is obvious that, as the fluid level in the barrel contacts with the float 14, the latter will rotate member 45 upwardly, thereby releasing hook 45 from the pawl and permitting the spring 27 to close valve 23, thus stopping the flow into the barrel.

- 10 A knurled hand disc 48, secured to a stud 49 and projecting into chamber 22, is provided as a means for closing the valve manually in the event of it failing to function properly. A triangular projection 50 on the end of stud 49, engages the underside of plate member 45. When the device is properly operating, the flat of projection 50 is normally parallel to the plate 45 allowing ample clearance between the two, for actuating the valve by the float. By rotating the disc 48, 20 one of the corners will rotate the plate 45 upwardly, closing the valve through the various members as herein described. A spring actuated plunger 51 engages detents in the disc providing a means for stopping the stud 25 50 in the open position.

The hinged hook 40 can be adjusted with respect to the pawl 31 so that various degrees of sensitiveness of action can be attained. This is accomplished by having the hinge 30 yoke 51 slidably mounted within the nipple 52, the latter being threadably secured to the body member 20. By detaching the threaded cap 53 from the nipple 52 and rotating set screws 54 which has a head swivelly mounted in yoke 51, the said hinge hook 35 can be adjusted in either direction, thus preventing a greater or lesser surface to the pawl 39 consequently requiring a greater or lesser time interval for the release of said pawl 39 to close the valve 23. The valve 40 stem has a set screw 52^a threadably mounted therein, and is provided for adjusting the valve 23.

I claim:—

- 45 1. A device of the class described comprising a main body having a valve slidably mounted therein, a shaft having a lever extending therefrom, a lifter hingedly connected to the end of said shaft and adapted 50 to lift the valve, an actuating lever extending from the opposite side of said shaft, a plunger rod in pivoted engagement with the actuating lever and extending upwardly through the body, a push button formed to the upper end of the said rod, means for opening the valve by depressing the push button, and means for varying the time of closing of the valve.

- 55 2. A device of the class described comprising a main body having a valve and a piv-

otally mounted shaft therein, a lever extending outwardly and having a hinged lever rod in engagement with the valve member, a similar lever extending from the other side of the shaft having a push button and 65 plunger pivotally secured thereto, a pawl formed to the end of last named lever, a hinged hook member adapted to engage said pawl and retain the valve in open position, means for releasing the hook from the pawl, 70 and means for securing the device.

3. A device of the class described comprising a main body having a valve and lever member mounted therein, a push button and plunger rod engaging one of said rods and 75 adapted to depress the same, a pawl at the end of said lever, a nipple threadably secured to the main body, a yoke member slidably mounted within the nipple having a hook hingedly secured thereto, a set-screw 80 threadably secured in the nipple and adapted to extend or retract the hinged hook with respect to said pawl, means for opening said valve, and means for closing said valve by a float movement.

4. A device of the class described comprising a main body and a tubular member extending downwardly therefrom, a valve and valve actuating levers within the main body, a hinged hook adapted to normally engage 90 one of said levers when the valve is open, and having a plate extending therefrom, a threaded stem and hollow float suspended from the said plate, and adapted to arcuately rotate the hinged hook, a triangular stud engaging the underside of the plate member, a hand disc secured to the said stud exterior of the main body and adapted to rotate the said triangular stud and close the valve when the stud corners lift the said plate, and 100 means for opening the said valve by depressing a push button.

5. A device of the class described comprising a main body and a tubular member extending downwardly therefrom, a valve and 105 valve stem, a set screw threadably mounted within the valve stem, valve actuating levers within the said body member, a lifter stem connected to the end of one of said levers and having the tip thereof engaging the 110 valve stem set-screw, a hinged hook engaging the other lever when the valve is open, a plate extending from the said hinged hook, a threaded stem and hollow float suspended from the said plate and adapted to arcuately 115 rotate the hinged hook and means for closing the valve manually.

In witness whereof we affix our signatures.

ANTON MATUSCHAK,
ALBERT LANGSCH.
